UNITED STATES PATENT OFFICE.

NELL JOHNSON, JOHN J. JOHNSON, AND EDWARD JOHNSON, OF NASHOTAH, WISCONSIN.

TRACTION-ENGINE.

SPECIFICATION forming part of Letters Patent No. 307,771, dated November 11, 1884.

Application filed February 28, 1884. (No model.)

To all whom it may concern:

Be it known that we, NELL JOHNSON, JOHN J. JOHNSON, and EDWARD JOHNSON, citizens of the United States, residing at Nashotah, in 5 the county of Waukesha and State of Wisconsin, have invented certain new and useful Improvements in Portable Steam-Engines; and we do hereby declare the following to be a full, clear, and exact description of the invention, 10 such as will enable others skilled in the art to which it appertains to make and use the same, reference being had to the accompanying drawings, and to letters or figures of reference marked thereon, which form a part of this 15 specification.

Our invention relates to improvements in portable steam-engines, and pertains to the devices and their adjustment for communicating motion from the crank-shaft to the traction-wheels, whereby the engine may be propelled from place to place by the application of steam-power.

Our invention is further explained by reference to the accompanying drawings, in which 25 Figure 1 represents a side view. Fig. 2 is a vertical section drawn on line xx of Fig. 1. Figs. 3, 4, and 5 are details.

Like parts are represented by the same reference-letters throughout the several views. 30 The boiler A, engine B, crank-shaft C, fly-wheel D, traction-wheels E E and F F, and axles G and H are all constructed and arranged in the ordinary manner.

To the side of the boiler A, and immediately in 35 front of the combustion-chamber, are attached the heavy iron brackets I I, upon which the journal-boxes J J are supported. The brackets I I are adapted to be secured to any boiler by screw-bolts fitting into screw-cut holes formed 40 therefor through the sides of the boiler, and all the parts are so constructed as to be easily attached to the various forms of portable engines and boilers now in use, as well as to be applied to new work in the process of construction.

To the inside of the two rear wheels, E E, is clamped or otherwise secured the sprocket-wheel K, to which motion is communicated from the crank-shaft C through the sprocket-wheel L, sprocket-chain M, sprocket-wheel N, 50 shaft O, sprocket-wheel P, and sprocket-chain

Q. The journal-boxes J are attached to the brackets I by bolts R R, which pass down through the slots S, having heads beneath the lower surface of such brackets. The slots S 55 permit the journal-boxes to be moved toward the right or left, as may be required, to give the required tension to the sprocket-chains, and when properly adjusted are rigidly held in place by tightening the nuts on the bolts R R. 60

The sprocket-wheels P P, one of which is shown in detail in Figs. 3 and 4, consist, respectively, in the disks or flanges T T, which are rigidly keyed to the shaft O and the annulus U, having sprocket-teeth V and inward-projecting ratchet-teeth a. The annulus U is supported upon and held in place by the disks T T, around which it is adapted to revolve, either with or independently of said disks. When, however, the disks T T are turned forward in the direction indicated by the arrow, the ratchet-teeth a engage one or both of the pawls b b, whereby motion is communicated from the shaft O through the pawls b b and disks T T to the annulus U, and from thence 70 through the sprocket-chain Q to the sprocket-wheels K and the traction-wheels, as mentioned. It is obvious that by thus connecting the sprocket-wheel by the pawls and ratchet to the shaft we are enabled to draw the vehicle 75 forward by external appliances without moving the engine, as the annulus U is free to turn around the shaft O and disks T T without communicating any motion to the chain M or engine. It is also obvious that when turning a 80 corner or describing a circle the outside traction-wheel is free to revolve as much faster than the inside traction-wheel as may be required by the additional space over which it travels, as the annulus with its ratchet-teeth 85 will be free to move forward over the pawls b b without communicating motion to the disks T or shaft O. When desirous to communicate a backward movement to the vehicle by the action of the engine, it becomes necessary to 90 connect the annulus U with the disks T T that they will both rotate backward together. This end is accomplished by inserting a bolt or key, "A", through the hole A', formed through the annulus U and disks T T, whereby it is 95 obvious that as the annulus is rotated backward in the opposite direction to that indi-

cated by the arrow (which is done by reversing the engine) said shaft O and disks T T will carry with them the annulus U, whereby a reverse movement will be communicated 5 through the chains Q to the wheels K, and from thence to the traction-wheels, and the vehicle will be caused to move rearward.

Having thus described our invention, what we claim as new, and desire to secure by Letters 10 Patent, is—

1. In a traction-engine, the combination, with the sides of the boiler, of the supporting-brackets I I, rigidly affixed to the sides of the boiler, said brackets having slots S S, the adjustable journal-bearings J J, bolts and nuts R R, the shaft O, and the mechanism driven thereby, substantially as and for the purpose 15 set forth.

2. In a traction-engine, the combination, 20 with the respective ends of shaft O, interposed between and connected by chains and gears with the crank-shaft of the engine and the shaft or axle of the traction-wheels, of the sprocket-wheels P, consisting, respectively, in the disks T T, keyed rigidly to the supporting-shaft O, pawls b, and annulus U, having sprocket-teeth 25 V and ratchet-teeth a a, said sprocket-wheels

being adapted to communicate a forward movement to the rear traction-wheels as they are rotated forward, and to permit said rear traction-wheels to move forward when drawn without moving the engine, substantially as and for the purpose specified. 30

3. The combination of shaft O, disks T T, rigidly keyed on said shaft, annulus U, adapted to revolve both with and independently of said disks, with the pin or key A', adapted to be inserted through key-hole A', provided therefor through said annulus and disks, whereby said disks and annulus are locked together, substantially as and for the purpose 35 specified. 40

In testimony whereof we affix our signatures in presence of two witnesses.

NELL JOHNSON.
